UNITED STATES PATENT OFFICE.

GEORGE E. SCHUMAN, OF LOUISVILLE, KENTUCKY, ASSIGNOR TO ABRAM G. NESBITT,
OF WILKES-BARRE, PENNSYLVANIA.

CALCULATING-MACHINE.

13,334.

Specification of Reissued Letters Patent. Reissued Dec. 5, 1911.

Original No. 824,510, dated June 26, 1906, Serial No. 275,373. Application for reissue filed June 10, 1908.
Serial No. 437,762.

To all whom it may concern:

Be it known that I, GEORGE E. SCHUMAN, of Louisville, in the county of Jefferson and State of Kentucky, have invented certain new and useful Improvements in Calculating-Machines; and I hereby declare that the following is a full, clear, and exact description of the same, reference being had to the accompanying drawings, which form 10 part of this specification.

This invention is an improvement in calculating machines; and its objects are to provide a machine capable of performing operations in addition with accuracy and rapidity, to provide improved registering mechanism, to provide novel key mechanism, to provide novel mechanism for arresting or detaining the registering levers when no keys pertaining thereto are depressed, to provide novel carry-over mechanism, to provide a novel total-indicating mechanism, to provide a novel mechanism for indicating the last item recorded until the next is being recorded, so that the operator can always see upon returning to the machine what was the last item recorded without having to inspect the printed record, to provide novel printing mechanism for recording the items and totals, to provide a novel type-hammer-locking mechanism, to provide a novel type alining mechanism, to provide a novel totaling mechanism whereby the totals may be ascertained and printed at any time, to provide a novel mechanism for indicating on the record whenever a total has been taken or the machine reset to "zero", to provide novel paper carriers, to provide novel repeating mechanism whereby items may be repeated without resetting the keys and to provide a novel error-key whereby the keys may be released without operating the machine in case an error has been made in depressing the keys.

The invention will be clearly understood from the following description, and the features and combinations of parts embodying the invention for which protection is desired are summarized in the claims following the description of the machine as illustrated in the accompanying drawings, in which—

Figure 1 is a front elevation of the ma-

chine with the outer casing broken away or removed, so as to show the operative parts. 55 Fig. 2 is a right-hand elevation of the machine with the side of casing removed. Fig. 3 is a left-hand elevation of the mechanism with the left-hand side of casing removed. Fig. 4 is a vertical section on line 4—4, Fig. 60 1. Fig. 4* is a detail view of the "total indicator recording mechanism." Fig. 5 is a detail view of the printing mechanism. Fig. 6 is a detail sectional elevation showing the parts in the positions assumed when the 65 hand lever is thrown forward. Figs. 7 and 8 are detail side and front views of one of the "item indicating" disks detached. Fig. 9 is a detail plan view of the "carry-over" devices in Fig. 3. Fig. 10 is a detail view 70 of the printing mechanism indicating a hammer printing. Fig. 11 is a detail view of the ribbon-actuating devices. Fig. 12 is a detail view of the paper-carriage adjusting plate. Fig. 13 is a detail view showing 75 the registering-wheel pawls thrown into totaling position.

The machine embodies a plurality of adding mechanisms arranged side by side and each constructed substantially alike and arranged as usual so that the "units-wheel" carries over at the "tenth" unit to the "tens-wheel" and so on up to the total capacity of the machine. There is one set of such mechanisms for each denomination in 85 the decimal notation up to the capacity of the machine, which can be made of any desired capacity by simply adding additional duplicate mechanisms.

The registering mechanism.—The registering-wheels 1 are loosely mounted side by side on a shaft 1*, journaled in the sides of the main frame of the machine. Each registering-wheel is constructed with a multiple of ten teeth—as shown, each has fifty 95 teeth—so that for each fifth of a revolution of the wheel ten numerals of its denomination will be counted and at every fifth of a revolution of a registering wheel of lower denomination, mechanism is actuated to 100 carry over or move the wheel of next higher denomination one tooth.

Loosely mounted on the shaft 1* beside each registering-wheel 1 is a vibrating lever 1*, which is thus pivoted beside the wheel 105 and swings in an arc concentric therewith.

The levers are thrown backward by springs 1^d when the levers are released from control of the resetting arm, hereinafter described. The springs 1^d are conveniently mounted on shaft 1^a, as shown. The upper end of each lever 1^b is provided with a laterally projecting finger 1^c, which moves in an arc when the lever is oscillated parallel with and beneath a related row of keys 3, and if any key in such row be depressed it will arrest the backward movement of such lever.

Each lever 1^b carries a pawl 1^e which is normally held in engagement with the teeth of the registering wheel by a spring 1^f, the pawl being pivoted on a pin or screw 1^g, attached to the lever. Pivoted on said pin 1^g is a second pawl 1^h, which extends in a direction opposite pawl 1^e and its tail engages a pin 1ⁱ on pawl 1^e, so that when one pawl is in engagement with the wheel 1 the other is out of engagement. Pawl 1^h is controlled by a spring 1^j, hung on the screw 1^g, with one end bearing on pawl 1^h and the other on pin 1ⁱ, so that the spring 1^j does not oppose the spring 1^f, which normally holds pawl 1^e in engagement with the wheel 1.

The tail of pawl 1^e projects beyond and above pawl 1^h and is provided with a pin 1^k, which at the proper times is engaged and depressed by suitable devices, hereinafter explained, to throw pawl 1^h into engagement with the wheel 1.

The levers 1^b are normally held in forward position against the action of springs 1^d by means of a pusher 1^m, attached to shaft 1^a, said pusher, as shown, being in the form of a bail shaped bar. The pusher 1^m is adapted to engage projections 1ⁿ on levers 1^b, as shown, so as not to interfere with the pawls. The shaft 1^a is controlled by suitable springs, so as to normally throw the pusher forward.

As shown in Fig. 2, a segmental gear 1°, keyed on shaft 1^a, meshes with a segmental gear 2^a, on a shaft 2, journaled in the main frame parallel with shaft 1^a. Shaft 2 is provided with a hand lever 2^b, on its outer end, by which it can be rocked forwardly; but when the lever is released the shaft is rocked backward and normally held in rearmost position by means of a stout spring 2^c, attached to an arm 2^d on shaft 2 and to a suitable point on the main frame, as shown in Fig. 2. As shaft 1^a is geared to shaft 2, it is obvious that the normal position of shaft 1^a is that shown in Fig. 2, with the pusher 1^m holding all the levers 1^b in their foremost position. If desired, the return spring-impelled movement of shafts 2 and 1^a may be cushioned by a dash pot 2^e attached to an arm 2^f on shaft 2 and engaged by a plunger attached to a rod 2^g,

pivotedly connected to the frame, as shown 65 in Fig. 2.

The key board.—As shown, there are nine keys in each row (one row for each denomination). These keys 3 are vertically movable, and their stems are mounted in slotted plates 3^a, attached to the frame, as shown. The lower ends of the first eight key stems are curved so that their extremities will coincide with the arc traversed by the finger 1^c on the related lever 1^b and will be equidistant, so that the space traversed by the lever 1^b in moving from one key to the next will just suffice to move the registering-wheel 1 one notch or tooth. Each key is normally upheld by means of a suitable spring 3^b, attached to the key and to a suitable point on the upper plate 3^a, as shown in Fig. 2. Each key stem has a ratchet tooth 3^d on its side, which when the key is depressed catches under a swinging-catch plate 3^e, hung from the upper slotted plate 3^a and normally swung inward toward the stems by a spring 3^f, so as to lock any depressed key until after the registration has been effected, when it is automatically disengaged from the key, as hereinafter described. This plate 3^e, moreover, prevents more than one key being locked down successively in any one row, and only the last key depressed will remain down, for if the wrong key is depressed and locked the operator merely has to push down the right key, which as it descends swings the locking plate 3^e outward, releasing the previously depressed key, while the last depressed key is held down. Thus if the operator discovers an error in his keyboard before actuating the hand lever 2^b he can instantly correct it by merely depressing the proper keys without having any errors in computation arise.

Preferably the stem of the ninth key is short, and when "9" is to be added on any one wheel the lever 1^b meets no obstruction in its rearward movement until it strikes a stop bar 3^g which is permanently fastened at the rearmost limit of movement of the levers 1^b and serves as a common "ninth" stop for all the levers 1^b.

The registering lever detainer.—In order to prevent the lever 1^b moving rearward when no keys have been depressed in its related row, although it is released by the rearward movement of the pusher 1^m, I provide a retainer finger 3^h, which is attached to the forward end of the related catch plate 3^e and depends just in front of the lever 1^b when the latter is in foremost position, Fig. 2. When any key in such row is depressed, however, the catch plate 3^e is swung outward, so as to move the detainer 3^h out of the path of finger 1^c of the lever 1^b, and as the catch plate cannot swing back to in-

active position until all the keys are released the detainer remains out of the way until the lever 1^b has made its operative oscillation. The detainer 3^m is provided with a slanting guard 3ⁿ, which the lever 1^b will engage on its return movement (if the detainer has swung back to operative position) and push the detainer out of the way, so it will not be injured.

10 *The key release.*—After each registering operation it is necessary to release the keys prior to setting the next item, and this is done as follows (see Fig. 2). Arranged at the front of the key board and extending 15 past the forward ends of the several catch plates 3^e is a slide bar 4^k, which is suitably supported, so that it can be reciprocated longitudinally. This bar has a series of inwardly projecting pins 4^m, which project 20 near the adjacent ends of the catch plates 3^e, but lie normally out of contact therewith. Bar 4^k (see Fig. 1) is pivotally connected to one arm of a bell-crank lever 4^j pivoted on the frame with its free arm 25 lying below the keyboard in position to be struck by the free end of a vibrating lever 4, pivoted at 4^c to the side of the frame. Lever 4 has a depending arm 4^b, which extends downward toward a segmental gear 30 1^c on shaft^a. On the lower end of arm 4^b is pivoted a dog 4^e, which has a tooth depending beside segment 1^c and adapted to be engaged by a pin 1^p thereon. When 35 segment 1^c rotates backwardly, pin 1^p tilts the dog and passes thereunder without oscillating lever 4; but on the return movement of the segment pin 1^p engages the dog, and the latter being locked against a stop 4^f on arm 4^b said arm is swung forward, 40 raising lever 4 and causing its upper end to strike lever 4^j and cause it to move bar 4^k, so that pins 4^m thereon engage the catch-plates 3^e and swing them outward or away from the key stems, thus releasing all the 45 keys. The pin 1^p moves forward sufficiently to clear dog 4^e, whereupon arm 4^b and lever 4 are returned to normal position by a spring 4^x, and bar 4^k is also returned to normal position by a spring 4ⁿ.

50 *The carry-over.*—A laterally projecting pin 1^r is attached to the side of each wheel 1 adjacent each tenth tooth. (In the drawings there are five such pins on each registering wheel.) This pin is adapted to engage one arm of a bell-crank trip 5^a, pivoted on a swinging lever 5, hung on shaft 1^r beside the registering wheel and having its lower end guided in a slotted plate 5^x, the trip being controlled by a spring 5^b. The 55 lower arm of trip 5^a lies above a plate 5^c, loosely mounted on a transverse rod 5^d, said plate being upheld by a spring 5^e, and a tooth 5^f on plate 5^c engages a notch 5^g on a projection of the next adjacent lever 5

pertaining to the wheel of next higher denomination and locks this lever in rearmost position, as indicated in Figs. 2, 3, 4 against the tension of a spring 5^h which always tends to swing lever 5 forward. The lever 5 adjacent each wheel of higher denomination carries a pivoted dog 5ⁱ which is yieldingly held in engagement with the teeth of such registering-wheel by a spring 5^j. This dog will trail on the wheel when the lever 5 is swung outward, but will move 75 the wheel when the lever is swung inward. Any released lever 5 will be moved backward at the proper time by means of a bail 5^m, attached to a rock-shaft 5ⁿ, which is provided with an arm 5°, carrying a dog 5^p, 80 controlled by a spring 5^q, (see Fig. 2) said dog projecting into the path of a pin 1^r on segment 1^c, so that when said segment is rocked by the forward movement of hand-lever 2^b the pin 1^r will engage the dog and 85 push the lever 5 rearward until they are locked by the engaging plates 5^c, and on the return movement of the segment the dog 90 will yield and allow the pin 1^r to pass it without affecting the shaft 5ⁿ.

Now when a pin 1^r on a wheel 1 of lower denomination engages and actuates the related trip 5^a said trip depresses the adjacent catch-plate 5^c and causes it to release the lever 5 of the wheel of next higher denomination, whereupon the said lever is thrown forward by its spring 5^h. Then when the hand lever 2^b is drawn forward shaft 5ⁿ is rocked, as described, and bail 5^m 100 pushes the released lever 5 inward sufficiently to cause its dog 5ⁱ to turn its registering wheel one tooth, and thus effects the carry-over operation. If the wheel of higher denomination just referred to happened to stand at the ninth tooth at the time its lever 5 was released by the movement of the wheel of lower denomination, obviously a pin 1^r on such wheel would in such case be in the path of the trip 5^a on its 110 related lever 5, so that when said lever was swung backward by spring 5^h the trip 5^a thereon would be rocked by the pin 1^r on the stationary wheel and cause the next catch-plate to release the lever 5 of the next 115 wheel of higher denomination, so that when shaft 5ⁿ was rocked both wheels of higher denomination would be actuated and the carry-overs effected.

120 *The total-indicator.*—Each registering-wheel 1 meshes with a small ten-toothed pinion 1^u, loosely mounted on a shaft 1^v in front of the registering wheels, and each pinion 1^u has a numeral-disk 1^w, so that by reading the aligned numbers on said disk 1^w 125 at the sight-opening the total amount added by the registering-wheels can be ascertained.

The item indicator.—Opposite each registering wheel 1 is a pinion 6, loosely mounted on a laterally movable rod 6^a, which is supported on swinging hangers 6^b pivoted to the sides of the frame, as at 6^c. Each pinion 6 is provided with a numeral disk 6^d, and said disks and pinions are normally held at zero position by means of a coiled spring 6^e, one end of which is attached to the disk 10 and the other to an arm 6^f on rod 6^a, which arm 6^f also serves as a stop to engage a pin 6^g on the disk to arrest the return movement of the disk at zero position. Rod 6^a is moved in position to bring pinions 6 in mesh with 15 the registering wheels 1 by means of an arm 6^g, attached to one of the hangers 6^b and extending inward toward the segment 1° which segment has a cam portion 1^t (see Fig. 2) which engages the inner end of arm 20 6^g when the segment is rocked by the forward movement of hand lever 2^b and raises said arm, thereby swinging rod 6^a inward and causing pinions 6 to mesh with wheels 1 before the latter are rotated. After the 25 cam 1^t has raised arm 6^g the latter is upheld (during the return movement of hand lever 2^b and segment 1°) by means of a finger 5^s on shaft 5^a, which drops under a pin 6^h on arm 6^g (see Fig. 2) and remains there until 30 shaft 5^a is rocked by the next succeeding forward movement of the hand-lever 2^b. The pinion 6 comes into mesh with wheels 1 when the pinions are at zero position and remain in mesh therewith while and after the 35 wheels are moved to register. Consequently the number of teeth each wheel has moved will be shown by its related indicator-disk 6^d and by reading the alined numbers on such disks at the sight-opening or reading 40 point the amount of the last item just taken by the machine will be ascertained. This "item" remains visible until the operator has set the keys for the next item and moves hand-lever 2^b forward to register it, whereupon 45 the initial movement of shaft 5^a draws finger 5^s away from pin 6^h and permits arm 6^g to drop, and rod 6^a swings forward, taking the pinions 6 out of mesh with the registering wheels, this movement 50 of rod 6^a being accelerated by a spring 6ⁱ, and as soon as pinions 6 are out of mesh with wheels 1 springs 6^e throw disks 6^d back to zero position. Immediately thereafter and during the continuance of the forward 55 movement of hand lever 2^b cam 1^t again engages arm 6^g and returns the pinions 6 into mesh with the wheels 1 before they are actuated, and they remain in mesh therewith until the next initial forward movement of 60 hand-lever 2^b, as above described. Thus the operator can leave the machine at any time and always can see at a glance what was the last item recorded if he looks before again manipulating hand-lever 2^b.

65 The printing mechanism.—The machine

is provided with mechanism to print each item added on the machine as follows: Attached to the levers 1^b are curved type-carrying bars 7, each of which carries ten type characters, (numerals "0" to "9" inclusive). Each type character 7^a is radially movable in the bar and is held in position by a spring 7^b, which may be threaded through the several type, as shown, and permits each type to be projected outward at the printing-point when struck by a hammer 7^c, as hereinafter explained. The type-carriers 7 are arranged close together, so that impressions from the type thereon will be properly related. Each type hammer 7^c is mounted 70 on a lever 7^d, Figs. 3 and 4, which is loosely pivoted on a shaft 7^e; and is provided with an arm 7^f, by which the hammer is "cocked," a spring 7^k, connected to said arm and a point on the frame, being adapted to actuate 80 the hammer. The arms 7^f are engaged and moved inward to "set" the hammers by a push-plate 7^g, mounted on a bail 7^h, attached to shaft 7^e, plate 7^g lying behind arms 7^f and being normally held by a spring 7^l at such 90 an angle that when bail 7^h is swung inward plate 7^g will engage arms 7^f and push them inward, setting the hammers against the resistance of springs 7^k. After the type 95 are in position to print, plate 7^g, which continues to move inward, is tripped by means of a finger 7^m engaging a stop 7ⁿ, Figs. 3 and 4, and caused to release arms 7^f, whereupon springs 7^k throw the hammers against the type, and the latter are forced outward and 100 make an impression on the paper carried by the paper carriage, hereinafter described. The shaft 7^e is rocked at the proper time, so as to move plate 7^g, as described, by means of a crank arm 7^o, connected by a link 7^p, 105 with a pin 7^q on segment 2^a. (See Fig. 2). *The type alining device.*—Above shaft 7^e is a shaft 7^r, on which are arms 7^s that extend toward the hammers 7^c, but terminate below the tops thereof. To these arms 7^s is 110 pivoted a bail shaped bar 7^t, which is adapted to come underneath a row of alined types, preferably in a row beneath those at the printing point, and is then rocked so as to engage such types and bring them into exact 115 alinement, so that the printed record will appear perfect. The bail 7^t is moved rearward after the type-carriers have come to rest ready for the printing operation by means of a cam-slot 7^u in a plate 7^v attached 120 to shaft 7^e and actuated thereby, said slot 7^u being engaged by a pin 7^w, attached to shaft 7^e, so as to impart a proper rocking motion to shaft 7^r at the proper time and then hold said shaft momentarily at rest, a 125 suitable dwell being provided in slot 7^u for this purpose. While bail 7^t is thus held in its rearmost position a forwardly extending finger 7^x on the bail is engaged by the pusher 1^m, which at the moment is moving to its 130

5 rearmost position, and bail 7^c is elevated slightly so as to engage the type, as described, and hold them momentarily in alignment while the hammers strike them. Then as pusher 1^m moves back the bail is released, and the bail drops back out of the way as the shaft 7^e returns to normal position. In order to align the "0" type on such carriers as have not been moved, I provide a pin 7^a on the inner end of each carrier (see Fig. 4) which will be engaged by bail 7^c during the aligning operation, if such carrier has not been displaced.

10 *The type hammer lock.*—In order to prevent the hammers printing ciphers to the left in cases where wheels of higher denomination have not been moved, I provide devices for locking such hammers when cocked, as follows:—On a bar 8, in front of and 15 slightly above the hammers, is a slide 8^a, which is provided with a depending part 8^b, that is adapted to pass in rear of the upper ends of the hammers after they are cocked and will prevent the hammers springing back when released by plate 7^c. As only the 20 left-hand hammers should be locked, the inward movement of slide 8^a is automatically controlled by the type-carriers, said plate being provided with a bayonet shaped finger 8^c which projects in rear of the hammers (see Fig. 5) and is adapted to contact with the type-carrier of the wheel of highest denomination that has been shifted and arrest the slide, so that it only locks the hammers to the left of such carrier. Consequently when plate 7^c disengages the arms 7^e the hammers locked by slide 8^a will not 25 actuate the type, while the other hammers will operate as above described. Then after bail 7^c has returned to its normal position, Fig. 4, the slide 8^a is moved back out of the way, so as not to interfere with the next setting operation of the hammers, and the released hammers fly back, but they are arrested by bail 7^c before they can engage the type. 30 Slide 8^a is moved inward at the proper time by means of a link 8^d, connected to an arm 8^e on a vertical rock shaft 8^f, a spring 8^g drawing the slide inward (when permitted) 35 until it is arrested by finger 8^c striking a type carrier, as above explained. The slide is positively moved out of the way at the proper time and held out of the way until the plate 7^c cocks the hammers by means of 40 a pin 8^h on shaft 8^f, which is engaged by a catch 8^m on arm 7^e attached to shaft 7^e, so that when the shaft 7^e is rocked backward slide 8^a is moved to the left clear of the hammers. Shaft 7^e returns before slide 8^a should 45 be released. Consequently a bell crank shaped detent 8ⁱ is pivoted beside shaft 8^f in position to drop in front of pin 8^h and lock the latter in the position to which it has been drawn by catch 8^m (see Fig. 2) and 50 hold it while shaft 7^e and catch 8^m rock for-

ward and until a pin 8^a on link 7^p strikes the upstanding arm of the detent and causes it to disengage pin 8^h, whereupon spring 8^g throws the slide into locking position until it is arrested by finger 8^c striking a type carrier, as indicated in Fig. 5.

55 *The totaling mechanism.*—In order to print the total amount which has been added at any time, I provide the following devices (see Fig. 3). A key stem 10 is arranged at one side of the machine and is pivotally connected at its lower end to an arm 10^a on a shaft 10^b, which shaft has a series of fingers 10^c extending inwardly and normally overlying the pawls 5ⁱ (see Fig. 4) 60 so that when the key is depressed said fingers will disengage said pawls 5ⁱ from the wheels 1. The stem 10 is also pivotally connected to an arm 10^d on a shaft 10^e, Fig. 3, to which is attached a series of curved arms 85 10^f, which extend over the pawls 1ⁱ and are adapted (when stem 10 is depressed) to engage pins 1^k on the tails of pawls 1ⁱ and throw said pawls out of engagement with wheels 1 and at same time cause pawls 1^h to 70 engage with said wheels, the arms 10^f being long enough to hold the pawls in this condition during the entire movement of levers 1^b, the pawls 1ⁱ trailing under the curved arms. Arm 10^d is connected by a link 10^h 75 with a bell crank 10ⁱ, pivotally connected to the bar 4^k, so that when arm 10^d is depressed said bar 4^k is shifted so as to swing the catch plates 3^m and move detents 3^m out of the way of levers 1^b and hold them so as 80 long as key 10 is depressed. On shaft 10^b is a pin 10^l, Fig. 2, which is adapted to engage a lug 5ⁿ on shaft 5^m and rock said shaft, so as to disengage finger 5^a from pin 6^b and allow rod 6^a to swing pinions 6 out of mesh 85 with the wheels 1, as above described. All these operations being performed on the depression of stem 10, the operator then draws hand-lever 2^b forward, freeing levers 1^b 90 from pusher 1^m, whereupon said levers 1^b are thrown backward by their individual springs, and as pawls 1^h are then in mesh with wheels 1 said wheels will be rotated backward until their pins 1^e come against the rear side of the trip 5^a, Fig. 4, whereby 95 the wheels are arrested with the small wheels at "0," and the proper type will then be arrested at the printing point, and the total is printed immediately thereafter before the hand-lever completes its forward stroke. If the stem 10 be held down while the hand-lever 2^b is making its return stroke, the numeral disks 1^w will remain reset to 100 zero; but if the stem 10 be released before the hand-lever is returned, pawls 1^h will engage the wheels 1, and the wheels 1 and the numeral disks will assume the same positions they had before the total key was depressed.

105 The totals and subtotals may be printed 110 115 120 125 130 135

in a distinguishing ink, as hereinafter explained.

In order to prevent the total key being depressed accidentally or to prevent said key from springing up to normal position, except when hand lever 2^b is in extreme forward or rearward positions, a flanged guard segment 11 is attached to shaft 1^a (see Fig. 3), said segment moving under 10 (or over) a pin or roller 10^a on the rearwardly-extending arm of lever 10^d and effectively preventing depression or release of the total key stem 10 at the wrong time.

The printed zero indicator.—If the stem 15 10 be held down during the entire totaling operation and the machine reset to zero, the fact will be automatically indicated on the printed record by the following mechanism when the first item in a new transaction is 20 printed. On the shaft 7^r beside the bail 7^t is loosely mounted a type lever 17, carrying on its upper end a single type character 17^a, preferably an asterisk or other peculiar character which lies in position to print on 25 the paper alined with the other type at any printing operation when said type lever 17 is permitted to operate. This lever 17 is controlled by a spring 17^b. The lower end of the lever projects below the shaft 7^r, and 30 on this lower end is a pin 17^d which normally contacts with one of the members of bail 7^t, which rocks the lever 17 as it vibrates and ordinarily keeps the type-lever 17 from printing. Below lever 17, but adjacent 35 its lower end, is a bell crank catch-lever 17^t, pivoted on a stud 17^e and controlled by a spring 17^h. One arm of this lever projects toward pin 17^d and is adapted, if raised, to engage said pin and prevent 40 the lever 17 returning to normal position after being moved backward by bail 7^t. The lever 17^t normally lies below the path of pin 17^d; but it is connected by a spring 17^k and link 17^m to an arm 17ⁿ on shaft 10^b, 45 so that when the stem 10 is depressed the lever 17^t is lifted against pin 17^d placing spring 17^h under tension, and when bail 7^t is drawn forward the pin 17^d will move down, allowing the catch lever 17^t to be 50 drawn forward by spring 17^k, so that if the total key is held down during the entire oscillating movement of hand-lever 2^b the catch lever 17^t will remain in front of pin 17^d in position to engage said pin and to 55 lock lever 17 when total-key is released, (see Fig. 4^a), but at the next printing operation of the machine (preceding which plate 7^s is swung inward to cock the type hammers) as above described, about the time that plate 7^s 60 is tripped to release the type-hammers, the lever 17^t is tripped, so as to release type-lever 17 and allow it to make an impression on the paper lever 17^t being tripped at the proper time by means of a finger 17° on 65 bail 7^t. (See Figs. 4 and 4^a). The asterisk

or character printed by lever 17 will denote unmistakably on the record that a total had just previously been printed and that the numeral disks 1^w had been reset to zero. If the total key is released at end of forward movement of hand lever (as in taking sub-totals), the catch lever 17^t will drop back to normal position and will not lock lever 17, and at the next printing operation of the machine type lever 17 will not make an impression on the paper.

The paper carrier.—At the rear of the machine is a platen roller 9 and coacting feed rollers 9^a 9^b, which are journaled in brackets 9^c and 9^e, mounted on a frame 9^d, 70 which frame is slidably supported on a rod 9^f, attached to the main frame (see Fig. 3). The platen frame 9^d is provided with a rearwardly extending finger 9^g which can be engaged with any one of a series of notches 9^h 75 in a transverse plate 9ⁱ attached to the main frame, and which will hold the carriage in any position to which it is adjusted by hand, the platen carriage being raised or tilted by hand so as to disengage finger 9^g 80 from any notch and then the carriage moved right or left until the finger is under the desired notch, when the carriage may be released and remains in such position until again shifted by hand. The platen roller 9 85 is provided with the usual finger manipulating button 9^j on one end, also with a ratchet 9^k which is engaged by a pawl 9^l pivotally mounted on a swinging plate 9^m, to which is attached a longitudinally disposed 90 bar 9ⁿ, that extends the length of the roller 9. When the platen carriage is lowered, this bar 9ⁿ lies in front of an oscillating lever 9°, which is loosely mounted on shaft 7^r and vibrated by means of a link 9^p, attached to arm 5° on the shaft 5ⁿ. (See Fig. 2). Lever 9° oscillates bar 9ⁿ, so as to rotate platen 9 and turn the paper forward 100 one line after each printing operation. The bar 9ⁿ may be retracted by a spring 9^p. By 105 this construction a series of columns may be printed on the same sheet of paper at successive operations, the paper carriage being shifted by hand from one notch 9^h to another after each column is finished.

The inking ribbon is passed between the type and platen, as indicated in Figs. 2 and 3. Preferably I employ a two-color ribbon, and the ribbon spools 9^r are slidably keyed on rotatable rods 9^s (see Fig. 5) 110 120 which spools are yieldingly upheld by springs 9^t. The rods have ratchets 9^u on their lower ends engaged by oscillating dogs 9^v, which are shifted by any suitable means so as to enable the ribbon to be wound or unwound from one spool to the other at will. The ordinary item printing may be done on the lower side of the ribbon, which, for example, may be blue, while the total and subtotal printing may be effected from the up- 125 130

per part of the ribbon which is, for example, red. In order to shift the ribbon spools at the proper time, curved fingers 10^a are attached to shaft 10^c, and when the total key 5 is depressed, as above explained, said fingers 10^a contact with and depress the ribbon spools 9^a, so that the red part of the ribbon is between the type and paper, and held there while the total or subtotal is printed. 10 When the item 10 is released fingers 10^a rise and springs 9^b raise the ribbon-spools so as to bring the blue ribbon into place for making the ordinary item-records.

The repeat device.—If the operator desires to repeat the same item a number of times, he can do so without setting the keys but once by means of the "repeating key" 14, the stem 14^a of which normally lies just above the tail of the trip pawl 4^a on the arm 20 4^b of key release lever 4. When key 14 is depressed, its stem engages the tail of dog 4^a (see Fig. 2) and will hold said dog out of the path of pin 1^b, so that the key release lever 4 will not be operated, and the 25 item may be printed a number of times in succession by holding key 14 down and oscillating hand lever 2^b, as above described. Stem 14^a may be provided with a notch 14^c which can be engaged with the upper guide 30 plate to lock the key depressed by simply pushing the key 14 to one side after it is depressed. When the key 14 is released, it is thrown upward by a spring 14^d and remains out of the way, and the lever 4 then causes 35 the release of the keys as above described.

Error-key.—If at any time the operator should set up a wrong item on the keyboard and discover his error before printing it, he can correct it by depressing a key 13, whose 40 stem 13^a extends into close proximity to a rearward extension 4^c of lever 4, (see Fig. 2) and by depressing this key lever 4 is oscillated and caused to shift release-bar 4^b, and all the keys are released and may be 45 reset.

Abnormal movement or casual displacement of the wheels 1 is prevented by frictional pawls 12, actuated by springs 12^a.

I do not limit myself to details of construction as shown, as these may be modified in many particulars without departing from the spirit of my invention.

Having thus described my invention, what I claim, and desire to secure by Letters Patent, is—

1. In a calculating machine, the combination of a registering wheel, an actuating lever pivoted beside said wheel and swinging on an arc concentric therewith, a spring 50 for moving said lever in one direction, a more powerful spring for returning said lever to normal position, a hand lever for overcoming the more powerful spring, and means on said lever for engaging the wheel, substantially as described.

2. In combination a series of registering wheels, a vibrating lever pivoted beside each wheel, opposite dogs carried by said levers adapted to engage the adjacent registering wheels and means for throwing either set 70 of dogs into operation, keys and connections for limiting the registering movements of the levers, means for returning the levers to normal position, and computing mechanism actuated by said registering wheels, substantially as described.

3. In a calculating machine, the combination of a series of registering wheels on one shaft, an actuating lever pivoted beside each wheel and swinging on an arc concentric therewith, springs for moving said levers in one direction, a more powerful spring for returning said levers to normal position, a hand-lever for overcoming the more powerful spring, and means on said levers for engaging the wheels, substantially as described.

4. In a calculating machine, the combination of a series of registering wheels on one shaft, an actuating lever pivoted beside each 90 wheel and swinging on an arc concentric therewith, a spring for moving said lever in one direction, a more powerful spring for returning said levers to normal position, a hand lever for overcoming the more powerful 95 spring, and means on said levers for engaging the wheels; with key controlled devices for arresting the registering movements of said levers, and means for carrying over from one wheel to the next higher, 100 substantially as described.

5. In combination with registering wheels, a vibrating lever pivoted beside each wheel and swinging on an arc concentric therewith, devices on said lever adapted to engage the wheel when the lever moves in one direction, keys and connections for limiting the operative movements of said levers; springs for moving said levers in one direction, a more powerful spring actuated device for returning the levers to normal position, and a hand-lever for overcoming the more powerful spring.

6. In combination with registering wheels loosely mounted on a common shaft, a 115 spring actuated lever pivoted beside each registering wheel and swinging on an arc concentric therewith, dogs on said levers adapted to engage the adjacent registering wheels, a pusher on said shaft adapted to return the levers to normal position and tension their springs, a rock-shaft, gearing between the rock shaft and the pusher shaft, a spring for moving said rock shaft in one direction, and a hand lever for moving it 120 in the opposite direction, substantially as described.

7. In combination with registering wheels, levers beside the wheels, dogs on said levers swinging on arcs concentric with the wheels,

and adapted to operate them, and means for vibrating said levers; with a series of key stems for limiting the operative movement of each lever, catch plates beside each row 5 of stems adapted to hold down depressed keys until the registering mechanism has operated; means for simultaneously moving all said catch plates to release the keys, and means, operated by the registering mechanism 10 whereby said release is not effected until after the registering mechanism has operated substantially as described.

8. In combination with registering wheels, vibrating levers beside the wheels, dogs on 15 said levers swinging on arcs concentric with the wheels, and adapted to operate them, and means for vibrating said levers; with a series of key stems for limiting the operative movement of each lever, swinging 20 catch-plates beside each row of stems adapted to hold down depressed keys until the registering mechanism has operated, a sliding bar for simultaneously moving all of said catch plates to release the keys, and 25 means, operated by the registering mechanism, whereby said release is effected after the registering mechanism has operated, substantially as described.

9. In combination, a series of rows of key- 30 stems, a swinging catch plate for each row of stems adapted to lock them in depressed position, a bar adjacent the ends of said catch-plate, and means on said bar adapted to engage the catch plates and swing them 35 away from the stems; with registering wheels, their actuating levers adapted to engage the stems of depressed keys, means for returning the levers to normal position, and means operated by said levers for actuating said bar so as to release the keys after 40 the registration is effected.

10. The combination of a set of registering wheels, their actuating levers, a set of key-stems for limiting the operative movements 45 of said levers, and means for resetting said levers; with catch plates for locking the key stems in depressed positions, a bar provided with pins adapted to engage said catch plates and disengage them from the 50 stems, and a vibrating lever and connections for operating said bar from and by the said actuating levers, substantially as described.

11. In combination with a registering wheel, an actuating lever pivoted beside the 55 wheel and swinging on an arc concentric therewith, the keys, and the key-stem catch plate; of a lever-detainer attached to said catch-plate, and adapted to prevent the forward movement of the lever until the catch 60 plate is swung to one side by the depression of a key stem, a spring for throwing the lever in one direction when released, a more powerful spring for returning it, and means for overcoming the more powerful spring.

12. In combination, a series of registering

wheels, their actuating levers pivoted beside the wheels and swinging on an arc concentric therewith, keys limiting the movement of each lever, and a key stem catch-plate for each row of keys; with a lever-detainer 70 attached to each catch-plate and adapted to prevent the forward movement of the related lever until the catch plate is swung to one side by the depression of a key stem, a spring for throwing each lever in one direction when released, a more powerful spring for returning it, and means for overcoming the more powerful spring.

13. In combination with adjacent registering-wheels, and means for operating said wheels; of levers hung beside said wheels and swinging on arcs concentric therewith, dogs on said levers adapted to engage the adjacent wheels, a catch-plate adapted to lock the levers in one position, a spring for 80 throwing each lever in one direction when released, a more powerful spring for returning it, and means for overcoming the more powerful spring, trips adapted to be operated by said wheels at every tenth 85 tooth, so as to release the catch of the lever of higher denomination, and means for vibrating said lever whereby the carry-over is effected, substantially as described.

14. In combination with adjacent toothed 90 registering wheels provided with pins at every tenth tooth, and means for operating said wheels; of levers hung beside said wheels and swinging on arcs concentric therewith, dogs on said levers adapted to 100 engage the adjacent wheel, a catch plate adapted to lock the levers in one position, trips adapted to be operated by said wheels at every tenth tooth, so as to release the catch of the lever of higher denomination, 105 a spring for operating the released lever, a more powerful spring for returning said lever to normal position, and means for overcoming the more powerful spring, substantially as described.

15. In combination with a set of registering wheels, having a multiple of ten teeth on their periphery, pins on each wheel adjacent every tenth tooth, a swinging lever beside each wheel and swinging on arcs concentric therewith, a pawl thereon in normal engagement with the wheels, a spring actuated catch plate for locking said levers in inoperative position, a trip on each lever adapted to be operated by the pin on the 120 wheel, and to release the catch of the adjacent lever of higher denomination, a spring for operating the released lever, a more powerful spring for returning said lever to normal position, and means for 125 overcoming the more powerful spring, substantially as described.

16. In a calculating machine, the combination of registering mechanism with means for indicating the last "item" registered,

and means for throwing the "item-registering" mechanism into mesh with the registering mechanism during the registering of an item, and for disengaging it from said 5 registering mechanism and resetting it to zero before the registering of the next item.

17. In a calculating machine, the combination with the registering wheels of numeral disks adapted to indicate the last 10 "item" registered, and means for throwing the disks into mesh with the registering wheels during the registering of an item, and for disengaging them from said registering wheels and resetting them to zero 15 before the registering of the next item.

18. In combination with registering wheels, and mechanism for operating them; of item indicating disks provided with pinions and mounted on a movable support, 20 means for normally holding said numeral disks at "0" position when out of mesh with the registering wheels; means for moving said disks into mesh with the registering wheels before the latter are operated to register an item; means for holding 25 said disks in mesh with the wheels after they have operated, so that the item registered can be read therefrom, and means for returning the disks to zero, before the next 30 operative movement of the registering wheels, substantially as and for the purpose described.

19. In combination with movable type-carriers of different denominations and 35 type hammers adapted to actuate the type at the printing point; of a movable slide adjacent the hammers adapted to contact with the displaced type carrier of highest denomination and arrest the slide in position to lock the hammers of type-carriers of 40 higher denomination, means for automatically throwing said slide into operative position after the type-carriers have reached their printing positions, but before the 45 printing operation, and means for returning the slide to inoperative position after the printing operation, substantially as described.

20. The combination of registering wheels, 50 type-carriers of different denominations controlled by said wheels, type-hammers adapted to engage the type at the printing point, and means for cocking said hammers; with a device for locking the hammers of all carriers of higher denomination whose registering wheels are not actuated; means controlled by the hammer cocking devices for releasing said locking device before the hammers are released; means for withdrawing 55 the locking device out of the way after the printing operation, and means for holding the locking device in retracted position until the hammers are ready for the next printing operation, substantially as described.

65 21. In combination, the registering-wheels,

their actuating levers, longitudinally movable type carriers of different denominations attached to said levers and oscillating type hammers adapted to actuate the type at the printing point; with a sliding locking plate 70 adjacent the hammers, a finger on said plate adapted to contact with the displaced type carriers of highest denomination, and arrest the slide in position to lock the hammers of any undisplaced type carriers of higher 75 denomination, a spring for automatically throwing said slide into operative position after the type carriers have reached their printing positions, but before the printing operation, and means for returning the slide 80 to inoperative position after the printing operation, substantially as described.

22. In combination, the registering wheels, their vibrating actuating levers, the curved type carriers of different denominations attached to said levers, oscillating type hammers adapted to engage the type at the printing point, and means for cocking said hammers; with a slide for locking the hammers of all carriers of higher denomination 90 whose registering wheels are not actuated; means controlled by the hammer cocking devices for releasing said locking plate before the hammers are released; means for withdrawing the slide out of the way after the 95 printing operation, and means for locking the slide in retracted position until the hammers are cocked for the next printing operation, substantially as described.

23. In a calculating machine, the combination of a registering wheel, a key controlled lever, a pair of dogs mounted on said lever, means for normally holding one dog in engagement with the registering wheel, and means for throwing said dog out of engagement when the other dog is thrown into engagement, substantially as described.

24. In a calculating machine, the combination of a plurality of registering wheels, a key controlled lever for each wheel, a pair of dogs mounted on each lever, means for normally holding one dog in engagement with the adjacent registering wheel, and means for throwing said dog out of engagement when the other dog is thrown into engagement and a computing train of disks actuated by said wheels, substantially as described.

25. In combination, a shaft, a series of registering wheels loosely mounted on the 120 shaft, a vibrating lever beside each wheel, opposite dogs carried by said levers adapted to be engaged with the adjacent registering wheel, means for holding one set of the dogs normally out of operation, keys and connections for limiting the registering movements of the levers, and means for returning the levers to normal position, substantially as described.

26. In combination with a set of register- 130

ing wheels having a multiple of ten teeth on their periphery, pins on each wheel adjacent every tenth tooth, a swinging lever beside each wheel, a pawl thereon in engagement with the wheels, a spring actuated catch plate for locking said levers in inoperative position, a trip on each lever, adapted to be operated by the pin on the wheel, and to release the catch of the adjacent lever 5 of higher denomination, a spring for retracting the lever when released; means for returning said lever to normal position, whereby the carry over is effected, and means for throwing the dogs out of operative position 10 when it is desired to take the total.

27. In combination with registering wheels, and vibrating levers for actuating said wheels pivoted beside the wheels and swinging on arcs concentric therewith, of a total 20 key and connections whereby when the total key is depressed the levers are permitted to turn the wheels until brought to "zero" position, substantially as described.

28. In combination, registering wheels, vibrating levers for actuating said wheels pivoted beside the wheels and swinging on arcs concentric therewith; and a total key and connections whereby when the total key is depressed the levers are permitted to turn 30 the wheels until brought to "zero" position; with type carriers attached to said levers and mechanism for taking an impression from the type to print the total before the total key is released, substantially as described.

29. In combination with registering wheels, vibrating levers for actuating said wheels, pawls carried by said levers adapted to operate the wheels in either direction, type 40 carriers controlled by said levers; and mechanism for taking an impression from the type after the registering wheels have come to rest; of a total key and connections for disengaging one set of dogs from the wheel 45 and throwing the other dogs into engagement therewith, mechanism for simultaneously releasing the levers, and means whereby the printing mechanism is operated to print the total while the said total key is 50 depressed.

30. In combination, registering wheels, vibrating levers for actuating said wheels, pawls carried by said levers adapted to operate the wheels in one direction, other pawls 55 carried by said levers adapted to engage the wheels and move them in the reverse direction, type carriers connected to and actuated by said levers, and mechanism for taking an impression from the type after the levers 60 have made their inward stroke; with a total key and connections for disengaging the first dogs from the pawls and throwing the reverse dogs into engagement therewith, mechanism for simultaneously releasing the 65 levers and means whereby the printing

mechanism is operated to print the total while the said total key is depressed.

31. In combination, registering wheels, vibrating levers for actuating said wheels pivoted beside the wheels and swinging on arcs 70 concentric therewith, springs for throwing the levers in one direction, a more powerful spring for returning the levers to normal position, and a hand lever for overcoming the more powerful spring; with a total key and connections whereby when the total key is depressed the levers are permitted to turn the wheels in the reverse direction until brought to "zero" position, substantially as described.

32. In combination, registering wheels, vibrating levers for actuating said wheels pivoted beside the wheels and swung on arcs concentric therewith, springs for throwing the levers in one direction, a more powerful 85 spring for returning the levers to normal position, and a hand lever for overcoming the more powerful spring; with a total key and connections whereby when the total key is depressed the levers are permitted to turn the wheels in the reverse direction until brought to "zero" position; type carriers attached to said levers, and mechanism for taking an impression from the type to print the total before the total key is released, substantially as described.

33. In combination, registering wheels, vibrating levers for actuating said wheels pivoted beside the wheels and swinging on arcs concentric therewith, movable type-carriers controlled by said wheels, and a printing mechanism for taking an impression from the type on said carriers when the wheels come to rest; with a total key and connections whereby when said key is depressed, the registering wheels are permitted to move back to "zero" position, and the total is printed, substantially as described.

34. In combination, registering wheels, vibrating levers actuating said wheels, an item indicator normally meshed with said wheels, movable type carriers controlled by said wheels, and a printing mechanism for taking an impression from the type on said carriers when the wheels come to rest; with a total key and connections whereby when said key is depressed the item indicator is thrown out of mesh with the registering wheels, the latter are permitted to move back to "zero" position, and the total is printed, substantially as described.

35. In combination with registering wheels, vibrating levers for operating said wheels pivoted beside the wheels and swinging on arcs concentric therewith, type carriers attached to said levers, mechanism for taking impressions from type on said carrier at each operation of the registering mechanism, and a total key and connections whereby upon the depression of said key the total 125 130

may be printed and the registering mechanism reset to "zero" at the will of the operator.

36. In combination, registering mechanism, type carriers controlled thereby, and mechanism for taking an impression from the type; with a total key and connections whereby when said key is depressed the total may be printed on the record in a distinctive color, and mechanism whereby at the next following printing operation a significant character indicating that the machine has been cleared, will be printed on the record simultaneously with the item recorded, substantially as described.

37. In combination, registering wheels, vibrating levers for operating said wheels, type carriers attached to said levers, mechanism for taking impressions from type on said carrier at each operation of the registering mechanism, and a total key and connections whereby upon the depression of said key the total may be printed; with mechanism whereby at the next succeeding printing operation a significant character, indicating that the machine had been cleared, will be printed on the record simultaneously with the item recorded, substantially as described.

38. In combination, registering wheels, vibrating levers for actuating said wheels pivoted beside the wheels and swinging on arcs concentric therewith, movable type carriers controlled by said wheels, and a printing mechanism for taking an impression from the type on said carriers when the wheels come to rest; with a total key and connections whereby when said key is depressed, the registering wheels are permitted to move back to "zero" position, and the total is printed and mechanism whereby at the next printing operation of the machine a significant character will be printed on the record indicating that the machine has been previously "cleared."

39. In an adding machine, the combination, with the clearing printing and adding mechanisms thereof, of means for automatically printing as an incident to the printing of an item, a suitable character to indicate the fact that the machine had been cleared before the printing of such item.

40. In an adding machine, the combination, with the clearing printing and adding mechanisms thereof, of means for automatically printing at the beginning of a list of items as an incident to the printing of the first item in the list, a suitable character to indicate the fact that the machine was "clear" when the list was begun.

41. In an adding machine, the combination, with the clearing printing and adding mechanisms thereof, of means for automatically printing a suitable character when the first item is printed as an incident to

the printing thereof to indicate the fact that the machine was "clear" at that time.

42. In an adding machine, the combination, with the clearing printing and adding mechanisms thereof, of means for automatically printing a suitable character only when the first item is printed by the machine after "clearing" and as an incident to such item printing in order to indicate the fact that the machine was "clear" when such first item was printed.

43. In an adding machine, the combination, with the clearing printing and adding mechanisms thereof, of means for automatically printing with the first item a suitable character to indicate the fact that the machine was "clear" when such item was printed.

44. In an adding machine, the combination, with the clearing printing and adding mechanisms thereof, of mechanism for automatically printing in association with the first item and as an incident to the printing thereof, a suitable character to indicate the fact that the machine was "clear" when such item was printed, such latter mechanism being normally in position to print such designating or indicating character.

45. In an adding machine, the combination, with the clearing printing and adding mechanisms thereof, of means for automatically printing in connection with and at one side of the first item printed after a "clearing" of the machine, a distinguishing character to indicate the fact that the machine was "clear" when such item was printed.

46. In an adding machine, the combination, with the clearing printing and adding mechanisms thereof, of a special printing device for automatically printing a distinguishing character when the machine is "clear" as an incident to the printing of the first item thereafter.

47. In an adding machine, the combination with the clearing printing and adding mechanisms thereof, of a special type bar or carrier bearing a distinguishing type character and means coöperating with said type bar to cause said character to be automatically printed whenever the machine is operated to print an item while in "clear" condition.

48. In an adding machine, the combination, with the clearing printing and adding mechanisms thereof, of a special type bar or carrier bearing a distinguishing type character, and means coöperating with said type bar to cause said character to be automatically printed in connection with the first item put into the machine after "clearing."

49. In an adding machine, the combination of the clearing mechanism and the printing mechanism thereof comprising a series of type bars or carriers located side

by side, a special type bar or carrier located at one side of said series of bars, and bearing a distinguishing character, and means co-operating with said special type bar to cause said character to be printed at one side of the first item of a column or list begun after the "clearing" of the machine.

50. In a calculating machine, the combination with mechanism for recording a series of operations and the result or total thereof, and means for clearing the machine of means for recording an indication in association with the first item of a recorded series, which is dependent for its 10 operation upon a previous clearing operation.

51. The combination of registering wheels, their actuating levers pivoted beside the wheels and swinging on arcs concentric therewith, type carriers attached to said levers, and key controlled means for varying the throw of said levers; type hammers adapted to engage the type at the printing point, a spring for actuating each hammer, means for cocking the hammers prior to the printing operation, and means for tripping said hammers at the proper time; with a "total-indicator" printing lever beside the type hammers, mechanism 20 whereby said lever is cocked by the hammer cocking means, means for normally keeping the total indicator from effective operation, and a total key and connections whereby said total indicator is permitted 30 to become active, substantially as set forth.

52. The combination of registering wheels, a vibrating lever beside each wheel, dogs on said levers, swinging on arcs concentric with the wheels and adapted to 40 move the wheels in one direction; a series of numbered key stems for limiting the movement of each lever, a swinging catch-plate beside each row of stems adapted to engage and retain any depressed key stem 45 until another stem is depressed, means whereby after the registering mechanism has been operated, all said catch plates are simultaneously disengaged from the stems, and means for returning the levers to normal 50 position.

53. In a calculating machine, the combination with the registering wheels; of means adapted to indicate the last "item" registered, comprising a set of numeral-disks, means for turning said disks by and from the registering wheels on recording an item, and means for resetting the said disks to "zero" before the registering of the next succeeding item, substantially as described.

60. The combination of registering wheels, vibrating levers for actuating said wheels, type-carriers attached to the upper ends of said levers, and key controlled means for limiting the throw of said levers; with

vibrating type hammers 7^a adapted to engage the type opposite the printing point, a spring for actuating each hammer, a pivoted push plate 7^b for cocking the hammers, means for tripping said push-plate to release the hammers at the proper time, and 70 a slide 8 for locking the hammers of the levers of higher denomination which have not been released by key action, substantially as described.

55. The combination of the registering 75 wheels, vibrating levers and connections for operating said wheels, key controlled mechanism for variously limiting the recording movements of the levers, type carriers attached to said levers, a platen, a series of 80 vibrating type hammers, springs for operating said hammers to make an impression; a push plate 7^b for cocking the hammer preparatory to the printing operation, and means for tripping said hammers at the 85 proper moment, a spring actuated slide 8 for locking the hammers of levers of higher denomination unless the said levers have been released, and means for returning the slide and hammers to normal position after 90 each actuation, substantially as described.

56. The combination of the registering 95 wheels, vibrating levers and connections for operating said wheels, and key controlled mechanism for variously limiting the recording movements of the levers; with curved type-carriers attached to said levers, a series of separately movable type mounted on each carrier, a platen, a series of vibrating type hammers 7^a, springs for operating 100 said hammers to make an impression, an oscillating pusher plate 7^b, means for causing said plate to cock the hammers preparatory to the printing operation, means for tripping said plate so as to release the hammers at the proper moment, and means for returning the pusher-plate and hammers to normal position after each operation, substantially as described.

57. In an adding machine, the combination, 110 with the clearing printing and adding mechanisms thereof, of a special printing device for automatically printing a distinguishing character in connection with the first item printed after the machine has been 115 "cleared."

58. The combination of registering wheels, actuating levers pivoted beside the wheels, type carriers 7 attached to said levers and key-controlled means for varying the throw 120 of said levers; type hammers 7^a adapted to engage the type at the printing point, a spring for actuating each hammer, a plate 7^b for cocking the hammers prior to the printing operation, and means for tripping 125 said hammers at the proper time; with a "total-indicator" printing-lever beside the type hammers, mechanism whereby said le-

ver is cocked by the hammer-cocking means; as my own I affix my signature in presence
means for normally keeping the total-indi- of two witnesses.
cator from effective operation, and a total
key and connections whereby said total-in-
dicator is permitted to become active, sub-
stantially as set forth.

In testimony that I claim the foregoing

GEORGE E. SCHUMAN.

In presence of—

VICTOR STEIN,
HENRY G. HILL.
